UNITED STATES PATENT OFFICE

CHARLES J. KIENZLE, OF COLUMBUS, OHIO, ASSIGNOR TO THE JEFFREY MANUFACTURING COMPANY, OF COLUMBUS, OHIO, A CORPORATION OF OHIO

ROPE WINDING DEVICE

Application filed November 1, 1928. Serial No. 316,536.

The present invention relates to certain new and useful improvements in rope winding devices adapted for use as the feeding and guiding mechanism of coal mining machines 5 of the type adapted to rest upon and slide in any direction over the floor of a mine.

The especial object of this invention is to provide, in a machine of the class described, improved winding mechanism comprising 10 two similar winding drums and ropes windable thereon associated with actuating and controlling mechanism whereby the ropes may be wound either simultaneously or separately at either a relatively high speed suitable 15 for handling the machine or at a relatively low speed suitable for feeding the cutting mechanism into the coal, or whereby the rope may be permitted to unwind against frictional resistance. The means whereby I 20 attain this object are fully set forth in the following specification and illustrated in the accompanying drawings wherein

Fig. 1 is a plan view of the preferred embodiment of my invention certain parts being broken away to reveal other parts.

Fig. 2 is a sectional view taken along the line II—II of Fig. 1.

Fig. 3 is a rear elevational view of the mechanism illustrated in Fig. 1 a cover plate being removed to show the feed controlling mechanism.

Fig. 4 is a sectional view taken along the line IV—IV of Fig. 1.

Fig. 5 is a fragmentary sectional view 35 taken along the line V—V of Fig. 1.

Fig. 6 is a fragmentary sectional view taken along the line VI—VI of Fig. 1.

Fig. 7 is a diagrammatic detail of the brake mechanism associated with the drum actuating mechanism.

Like numerals refer to similar parts in the several figures.

In the drawings I have shown the preferred embodiment of my invention which 45 is adapted for application to a coal mining machine of the well known shortwall type. As here shown the winding drums 1 and 2 upon which are windable the feed ropes 3 and 4, and their actuating mechanisms are 50 mounted upon a frame composed of three

castings 5, 6 and 7, which are securely joined together and to the frame 8 of the mining machine by the attachment bolts 9. The drums 1 and 2 are mounted to revolve about vertical axes symmetrically positioned one 55 at either side of the longitudinal center line of the machine. Since the winding drums 1 and 2 and their actuating mechanism are alike a description of one will apply to both.

The drum 1 is mounted to revolve upon a hub 10 which, in turn, is eccentrically rotatable about a stationary shaft 11 fixed to the frame of the machine. The hub 10 is provided with an arm 12 projecting horizontally to a position convenient to the hand 60 of the operator. Formed on the inner face of the drum 1 are internal gear teeth adapted to engage the teeth of a pinion 13 formed integral with the vertical shaft 14 which is journaled in a bearing 15 formed in the casting 6 of the machine frame. The shaft 14 is operatively connected with the armature shaft 16 of the mining machine motor through a train of gearing comprising a 65 planetary gear system which incorporates 70 mechanism whereby the actuation of the drum 1 may be controlled. Keyed to the upper end of the shaft 14 is a wheel 17 the hub 18 of which forms a journal for the shaft 14 in the bearing 19 of the top casting 7 of 75 the machine frame. The wheel 17 is provided with a downwardly projecting annular flange 20 having on its inner face gear teeth which engage the teeth of a plurality 80 of pinions 21. The pinions 21 are freely rotatable upon stud shafts 22 fixed to the spider 85 23. The spider 23 has inwardly projecting bearing elements 24 engaging a bearing surface formed on the hub 18 of the wheel 17 to maintain said spider in concentric relation with the shaft 14. Other pinions 25 are formed integral with the pinions 21, and these pinions 25 engage a spur gear 26 fixed to the hub of the worm wheel 27 which is 90 freely rotatable about the shaft 14. The worm wheel 27 engages a worm 28 formed integral with the worm shaft 29 and this worm shaft is supported in journal bearings 30 and 31 of the frame casting 6, which are 95 positioned in the central longitudinal ver- 100

tical plane of the machine coaxial with the armature shaft 16 to which the shaft 29 is connected by a shaft coupling 32. An annular flange 33 formed on the spider 23 is 5 embraced by a brake band 34 engagement of which resists rotation of the spider 23. A second ring gear 35 supported by but freely movable relative to the spider 23 engages the pinions 25 and this second ring gear 35 10 is embraced by a second brake band 36 whereby its rotation may be resisted.

The brake bands 34 and 36 are preferably formed of spring steel, or other suitable material, having a relatively high coefficient 15 of elasticity and they are preferably lined with fibrous material, as shown at 37 in Fig. 2, to provide a suitable coefficient of friction. The said brake bands are formed with a curvature of somewhat greater diameter 20 than the cylindrical surfaces which they embrace, and tend to spring away from said surfaces. A lug 38 fixed to one end of the brake band 37 engages the abutment 39 formed on the machine frame, and a similar 25 lug 40 formed on the other end of the brake band engages a finger 41 which projects upwardly from the feed nut 42. Similar lugs 43 and 44 attached to the brake band 34 engage the abutment 45 of the machine frame, 30 and the downwardly projecting finger 46 of the feed nut 42 respectively. The arrangement of these parts is such that movement of the feed nut 42 toward the right tightens the upper brake band 36 and releases the 35 lower brake band 34 while movement of the nut 42 toward the left tightens the lower brake band 34 and loosens the upper brake band 36. The brake band 36 is supported by the lugs 38 and 40 resting upon the upper 40 surface of a feed nut 42 and a lug 47 attached to the middle of the band and engaging a flange 48 of the machine frame. The 45 brake band 34 is similarly supported, the lugs 43 and 44 resting upon a surface 49 of the machine frame.

The planetary system associated with the drum 2 is similar to that above described, and because the worm wheel 27 engages the worm 50 opposite to the worm wheel 50 the drum 52 will be driven in a clockwise direction when the drum 1 is driven anti-clockwise. The 55 brake bands 51 and 52 are similar to those above described having similar lugs 53 and 54 engaging abutments 55 and 56 of the frame and lugs 57 and 58 engaging the fingers 59 and 60 of the feed nut 61.

The feed nut 61 is slidably supported in guideways 62 formed in the machine frame, and is screw threaded to a shaft 63 which 60 extends transversely of the machine. A flange 64 formed integral with the shaft 63 and a collar 65 screw threaded thereto engage opposite sides of a thrust collar 66 seated in a suitable recess of the machine frame which 65 acts to prevent longitudinal movement of

the shaft 63 in either direction. Fixed to the other end of the shaft 63 is a spur gear 67 which engages a similar gear 68 formed on a cylindrical sleeve 69 which projects through the machine frame and is journaled in a bearing 70 thereof. On the outer end of the sleeve 69 is formed a hand wheel 71 positioned convenient to the hand of the operator by manipulation of which the shaft 63 may be rotated in either direction to cause longitudinal movement of the nut 61 in the guideway 62. The feed nut 42 is slidable in a guideway 72 formed in the machine frame, and is screw threaded to a sleeve 73 which is mounted concentrically of the shaft 63 and adapted for rotation relative thereto. A flange 74 formed integral with the sleeve 73, and a collar 75 screw threaded thereto, engage opposite sides of the thrust collar 76 which is seated in a suitable recess of the machine frame and acts to prevent longitudinal movement of said sleeve in either direction. A spur gear 77 formed integral with the thrust collar 76 engages a similar gear 78 fixed to the shaft 79. The shaft 79 is rotatably mounted in the sleeve 69 and to its projecting end is attached a second hand wheel 80 by the manipulation of which the sleeve 73 may be rotated to move the feed nut 42 longitudinally in its guideways. The guideways 72 and 62 and the recesses for the thrust collars 66 and 76 are open rearwardly of the machine to facilitate the insertion or removal of the shaft 63 and its associated parts, and these parts are retained in operative position by the cover plates 81 attached to the frame castings 6 and 7 by suitable bolts.

When by manipulation of the hand wheel 80 the feed nut 42 is moved to the left the brake band 34 will be tightened to prevent rotation of the spider 23 thereby causing the vertical shaft 14 to be driven to wind the feed rope 3 at a relatively fast speed suitable for handling the machine over the mine floor. When the feed nut 42 is similarly moved to the right, the brake band 36 will be tightened to prevent rotation of the ring gear 35 and thereby cause the vertical shaft 14 to be driven to wind the feed rope 3 at a relatively low speed suitable for feeding the cutting mechanism into the coal. When the feed nut 42 is in the central, or neutral position, both of the brake bands 34 and 36 will be released from engagement with their respective driving elements, and the shaft 14 will remain idle. It is apparent that if either of the brake bands is partially tightened, permitting a greater or less degree of slippage between the brake band and its respective driving element, the speed of the shaft 14 will be proportionately reduced, and that these brake bands may act, under such circumstances, to retard rotation of the shaft 14 in a reverse direction.

By manipulation of the hand wheel 71 the shaft 82 may be driven in precisely the same manner as above described to cause the drum 2 to wind the feed rope 4 or to permit its 5 unwinding under frictional control. It will be noted that the hand wheels are so disposed relative to the associated drums that the wheel at the extreme left of the machine controls the drum at the left, and the wheel to the 10 right controls the drum at the right of the machine. This means that the relative positions of the wheels is indicative of the position of the drums controlled thereby.

By the arrangement of parts above described, I have produced a rope winding device having two winding drums either or both of which may be caused to revolve in a rope winding direction either simultaneously, or separately at either a relatively high or at a 20 relatively low speed or these drums may be permitted to revolve in an unwinding direction under frictional control.

What I claim is:

1. In a machine of the class described, the 25 combination with a frame, of a winding drum mounted thereon, a system of power transmission devices arranged to connect said drum with a source of rotative power, said system including two cylindrical brake elements and brake bands cooperating therewith, and a control device movable in one direction to engage with one of said brake bands and thereby cause rotation of said drum at relatively high speed and movable in the 30 other direction to engage with the other brake band and thereby cause rotation of said drum at relatively low speed.

2. In a machine of the class described, the 40 combination with a frame, of a winding drum mounted thereon, a system of power transmission devices arranged to connect said drum with a source of rotative power said system including two cylindrical brake elements and brake bands cooperating therewith, and a movable 45 control device having a finger adapted when said device is moved in one direction to engage and compress one of said brake bands and thereby cause rotation of said drum at relatively high speed and a second finger adapted when said device is moved in the other direction to engage and compress the other brake band and thereby cause rotation of said drum at relatively low speed as and for the purpose set forth.

55 3. In a machine of the class described, the combination with a frame, of a winding drum mounted thereon, a system of power transmission devices arranged to connect said drum with a source of rotative power said 60 system including two cylindrical brake elements and brake bands cooperating therewith, a control device movable in one direction to engage with one of said brake bands and thereby cause rotation of said drum at relatively high speed and movable in the 65

other direction to engage with the other brake band and thereby cause rotation of said drum at relatively low speed, and a screw arranged to move said control device in the preferred direction as and for the purpose set 70 forth.

4. In a machine of the class described, the combination with a frame, of two winding drums mounted thereon, systems of power transmission devices arranged to connect each of said drums with a source of rotative power said systems each including two cylindrical brake elements and brake bands cooperating therewith, two movable control devices and each adapted to cooperate with the brake bands of one of said transmission systems, a shaft extending transversely of the frame and screw threaded to one of said control devices, a sleeve mounted concentrically with said shaft and screw threaded to the other control device, two hand wheels mounted in bearings of the frame, and gears arranged to connect one of said hand wheels with said shaft and the other with said sleeve as and for the purpose set forth.

5. In a machine of the class described, the combination with a frame, of a winding drum mounted thereon, a system of plural speed power transmission devices arranged to connect said drum with a source of rotative power, said system including a plurality of co-axially disposed brake drums, brake bands operatively disposed relative to said drums, and means for selectively tightening said bands to control the transmission speed, said control means comprising a member reciprocable substantially tangentially of said bands and engageable therewith, said member in either direction of movement acting to simultaneously tighten one of said bands and loosen the other.

6. In a machine of the class described, the combination with a frame, of a winding drum mounted thereon, a system of plural speed power transmission devices arranged to connect said drum with a source of rotative power, said system including a plurality of co-axially disposed brake drums, brake bands operatively disposed relative to said drums, and means for selectively tightening said bands to control the transmission speed, said control means comprising a member reciprocable substantially tangentially of said bands and in a plane intermediate the planes of said bands and engageable therewith, said member in either direction of movement acting to simultaneously tighten one of said bands and loosen the other.

7. In a machine of the class described, the combination with a frame, of a winding drum mounted thereon, a system of plural speed power transmission devices arranged to connect said drum with a source of rotative power, said system including a plurality of co-axially disposed brake drums, brake bands

operatively disposed relative to said drums, and means for selectively tightening said bands to control the transmission speed, said control means comprising a threaded member extending substantially tangentially of said bands, a nut reciprocable along said threaded member upon rotation of the latter and engageable with the bands, said nut in either direction of movement acting to simultaneously tighten one of said bands and loosen the other.

8. In a machine of the class described, the combination with a frame, of a winding drum mounted thereon, a system of plural speed power transmission devices arranged to connect said drum with a source of rotative power, said system including a plurality of co-axially disposed brake drums, brake bands operatively disposed relative to said drums, and means for selectively tightening said bands to control the transmission speed, said control means comprising a threaded member extending substantially tangentially of said bands and in a plane intermediate the planes of said bands, a nut reciprocable along said threaded member upon rotation of the latter and engageable with the bands, said nut in either direction of movement acting to simultaneously tighten one of said bands and loosen the other.

9. In a machine of the class described, the combination with a frame, of a pair of drums mounted on said frame and rotatable about horizontally spaced vertical axes, and means for controlling rotation of the drums, said means including a pair of hand wheels external of the frame and rotatable in different planes about a common horizontal axis extending substantially parallel to the plane including the drum axes, the outermost of said wheels being associated with the nearer of the two drums and the other wheel being associated with the other drum.

10. In a machine of the class described, the combination with a rotatable element, of a source of rotative power and a pair of selected transmission trains for connecting said source and element to drive the latter, each of said trains including a brake drum and the brake drums being coaxially mounted, split brake bands operatively disposed relative to said drums with the ends of the one band in substantially registering relation to the ends of the other, means engaging the opposite ends of the two bands and reciprocable to tighten one of the latter upon movement in one direction and the other upon movement in the other direction, and means engaging the other ends of the bands to enable them to be tensioned.

11. In a machine of the class described, the combination with a rotatable element, of a source of rotative power and a pair of selected transmission trains for connecting said source and element to drive the latter, each of said

trains including a brake drum and the brake drums being coaxially mounted, split brake bands operatively disposed relative to said drums with the ends of the one band in substantially registering relation to the ends of the other, means engaging the opposite ends of the two bands and reciprocable substantially tangentially of the bands to tighten one of the latter upon movement in one direction and the other upon movement in the other direction, and means engaging the other ends of the bands to enable them to be tensioned.

12. The combination with a pair of co-axially disposed drums and brake bands therefor, of a band operator reciprocable substantially tangentially of the drums and having means engaging one of the bands to tighten it upon movement in one direction and means engaging the other band to tighten the latter upon movement in the opposite direction.

13. The combination with a pair of co-axially disposed drums and brake bands therefor, of a band operator reciprocable substantially tangentially of the drums and having means engaging one of the bands to tighten it upon movement in one direction and means engaging the other band to tighten the latter upon movement in the opposite direction, and means for reciprocating said operator comprising a rotary shaft on which the operator is screw-threaded.

In testimony whereof I have hereunto set my hand.
